ABSTRACT

A novelty lamp depicting a character formed of a vertical translucent tube having an electric light bulb therein and having the facial features of the character painted on the upper portion of the tube, a sleeve surrounding the lower portion of the tube representing the body of the character and provided with a plurality of slits extending vertically between an upper and a lower solid band, the lower band is moveable along the tube and can be rotated on the tube to simultaneously change the appearance of the body of the character and the quantity of light emitted by the lamp, and a cap fitted to the upper end of the tube having simulated hair attached thereto.

NOVELTY LAMP

BACKGROUND OF THE INVENTION

The present invention relates to novelty lamps, and, more particularly, to such lamps which depict a character.

SUMMARY OF THE INVENTION

It is an object of the present invention to provide a lamp depicting a character.

Another object is to provide such a lamp which can be adjusted to vary the quantity of light emitted.

Another object is to provide such a lamp in which the appearance of the character's body changes as the lamp is adjusted to vary the light emitted.

The foregoing objects are accomplished by providing a lamp comprising a vertical translucent tube surrounding an electric light bulb and having a character's facial features applied to the upper portion thereof, a slotted sleeve surrounding the lower portion of the tube depicting the body of the character, one end of sleeve being moveable on the tube to simultaneously change the appearance of the body and change the quantity of light emitted by the lamp, and means on the upper end of the tube depicting the character's head covering.

BRIEF DESCRIPTION OF THE DRAWINGS

A preferred embodiment of the invention has been chosen for the purposes of illustration and description and are shown in the drawings wherein:

FIG. 1 is an elevational view of a lamp according to the present invention adjusted so that minimum light is emitted;

FIG. 2 is an elevational view of the lamp of FIG. 1 adjusted to emit a greater quantity of light and change the shape of the character's body;

FIG. 3 is a sectional view taken along the line 3—3 on FIG. 1;

FIG. 4 is an elevational view of the lamp of FIG. 1 adjusted in a different manner to emit a greater quantity of light and change the appearance of the character's body.

DETAILED DESCRIPTION OF THE INVENTION

With reference to the drawings, there is shown a lamp according to the present invention which includes a translucent tube 10 having a short upper section 11 and a long lower section 12, a stand 14 for supporting the tube in a vertical position, facial features painted on the outer surface of the upper section 11, a substantially opaque sleeve 15 of flexible material surrounding the lower section 12, a cap 16 positioned on the upper end of the tube and simulated hair 17 glued thereto, and a socket 19 for receiving an elongated light bulb 20.

The stand 14 includes a ring 21 slidably engaging the bottom end of the tube 10, an inner ring member 22, three rods 23 having straight sections 24 extending from the inner ring member 22 through slots in the ring 21 and having curved sections 25 forming feet upon which the lamp stands. The ring 21 is welded to each of the straight sections 24 of the rods 23.

The tube 10 has the color of the skin of the character which the lamp depicts. The facial features include eyes 26, eyebrows 27, nostrils 29, and a mouth 30. The paints used to form these features are of suitable colors and are semi translucent so that light shining through

the tube from the interior thereof passes through the painted features to give the painted features a realistic appearance.

The sleeve 15 is tubular and has an annular band of tape 31 encircling its upper edge and an annular band of tape 32 encircling its lower edge. The sleeve is provided with a plurality of regularly spaced vertical slits 34 extending between the bands 31 and 32 throughout the circumference of the sleeve to divide the central portion of the sleeve into slats 35. The sleeve is sized to fit the tube snugly and, in assembling the lamp, after the sleeve is positioned on the tube the bands of tape are applied under tension to ensure a tight fit. The upper end of the sleeve is additionally glued to the tube to hold it stationary. The lower end of the sleeve is slideable vertically upon the tube to cause the sides of the sleeve to bulge separating the slats 35 as shown in FIG. 2. The band of tape 32 is applied with sufficient tension to provide a fit between the sleeve and the tube which is sufficiently close to enable it to remain in any position in which it is placed.

The sleeve 15 is made of a vinyl plastic sheet secured to fabric backing which is commonly referred to as "knit backed vinyl." The fabric backing faces the tube 10 and is of a different color than the outwardly facing vinyl. As shown in FIG. 4, when the band 32 is rotated on the tube 10, the slats 35 twist into an "S" shape. In this position, the center portions of the slats are disposed at an angle to the tube, one edge touching the tube while the other is spaced from the tube. In this angled position, the slats allow more light to be emitted, and, on one side of the lamp, the fabric backing of the sleeve 15 is revealed. This changes the appearance of the body by giving it a gradation in color from one side to the other.

The light bulb socket 19 is provided with a threaded stem 37 which extends through the ring 22, and a nut 39 is threaded onto the stem to lock the socket to the ring 22. An electric line cord 40 extends from the socket 19 through the stem and nut in the conventional fashion. The line cord is provided with a conventional line cord switch (not shown) for turning the elongated light bulb 41 on and off.

In operation, when it is desired that the lamp give a minimum amount of light, the band 32 is moved to its lowest position as shown in FIG. 1. In this position, the character depicted by the lamp has a slim appearance and emits light through the upper section 11 and through the thin slits 34. Enough light is emitted through the slits 34 to define the body of the character and make the sleeve appear to be vertically striped clothing.

When it is desired that the lamp give a greater amount of light, the band 32 can be slid upwardly to bend and separate the slats 35 to both emit a greater amount of light and give the character a roly-poly appearance as shown in FIG. 2. Alternately, the band 32 can be rotated on the tube to increase the emitted light and change the appearance of the body of the character from one having a solid color with bright vertical lines (at the slits) to one having a gradually changing color with bright "S" shaped lines.

It will be seen from the foregoing that the present invention provides a lamp depicting a character which can be adjusted to vary the quantity of light emitted and the appearance of the character depicted.

I claim:

1 A novelty lamp depicting a fanciful character comprising a vertical translucent tube of uniform cross-section throughout its length having open ends and having contiguous upper and lower portions respectively representing the head and body of the character; a stand engaging the lower end of the tube for supporting the tube in a vertical position in close proximity to a supporting surface; means for mounting an electric light bulb only within said lower portion of the tube on said stand; means on said upper portion depicting the head of the character including areas of pigmented film depicting facial features applied to the outer surface of said tube, a cap mounted on the top end of said tube, and means mounted on said cap to depict the character's head covering; and a flexible sleeve surrounding said lower portion of said tube depicting the body of

the character, said sleeve having upper and lower bands at the ends thereof and being provided with normally vertical slits to form vertical slats therebetween, said lower band being moveable vertically to simultaneously change the outline shape of the body and the quantity of light emitted by the lamp, said lower band also being rotatable on said tube to twist the slats and change the quantity of light and the appearance of the body without substantially changing the outline shape of the body and wherein the inner and outer surfaces of said sleeve are of different color and the center portions of said slots are twisted by rotation of said lower band to reveal their inner surface and thus give the body a two color appearance.
